UNITED STATES PATENT OFFICE.

HARRY S. DICKINSON, OF MOLINE, ILLINOIS, ASSIGNOR, BY MESNE ASSIGNMENTS, TO
BERRY SHOCKER INCORPORATED, OF WILMINGTON, DELAWARE, A CORPORATION
OF DELAWARE.

GRAIN SHOCKER.

Application filed March 17, 1922. Serial No. 544,514.

The shocker of the present invention is of the general type shown and described in the Bert C. Berry applications, Serial No. 318,738, filed August 20, 1919, and Serial No. 5 446,843, filed January 8, 1921; and the present invention is directed to numerous features of improvement in the structure and operation of the various working parts included in a shocker of the type indicated.

10 The grain shocker of this general type employs an open sided pan or sheaf receiver, into which the sheaves are dropped from the binder with which the shocker is associated. The sheaves fall into the pan with their 15 butts projecting forward and accumulate in the pan until the number required to constitute a shock has been accumulated. At this point trip mechanism is operated which drops the pan until the tread members with 20 which the pan is caused to engage the ground, after which a complete rotation of the pan is effected, upending or butting the shock upon the ground, and causing the pan to somersault over the top of the shock in its 25 return to normal or receiving position.

The pan and tread members are carried by a pivoted inner frame, and these elements in combination constitute in effect a dump cart, which in depositing the shock functions 30 in a measure independently of the four wheeled frame, which constitutes the supporting element for the pan and tread members while the shock is being accumulated.

The present invention is directed to the 35 following instrumentalities:

First, to the mechanisms provided for packing down the individual sheaves as they accumulate in the pan, until the resistance of the accumulating pile of sheaves against 40 the packer mechanism serves to effect the operation of trip mechanisms which release the pivoted inner frame and allow the tread members to engage the ground.

Second, to the means provided for steady- 45 ing the up-ended shock and preventing the effect of its acquired momentum from toppling over the shock as its butt end is deposited upon the ground and during the interval of time that the pan is passing forwardly over the top of the deposited shock.

Third, to the arrangement of the butting tines, which are designed to align the butts of the sheaves during the period of accumu-

lation, and to spread the butts laterally to afford an extended base for the completed 55 shock.

Fourth, to the mechanism for suspending the delivery of sheaves during the dumping operation by correlated mechanisms, which are effective to open the gate and allow the 60 delivery of sheaves only during the accumulating period.

Fifth, to the means for correcting the fore and aft alignment of the sheaves with respect to the pan.

Finally, to the general construction of the machine as a whole and the correlating and timing of the several mechanisms to operate in harmonious relation to one another.

5 Fig. 11 is a plan view of the shocker with the pan in receiving position; and

Fig. 12 is a side elevation viewed from the side adjacent the binder with the pan in receiving position.

10 The shocker is built within and supported by a main frame, which comprises a pair of spaced side rails 10, elevated at their forward ends 11 and connected through the medium of corner bracket castings 12 to a cross front rail 13 which is provided with an eye 14 to receive the rear end of a diagonally disposed draft bar 15, which is connected with the draft mechanism for the binder. The corner bracket castings 12 are 15 extended forwardly to afford socket journals 16 which receive the upper ends of caster pintles 17 which journal front caster wheels 18 located beneath the inner and outer front corners of the structure.

20 The frame is supported at its rear end by outer and inner ground wheels 19 and 20, which constitute the sources of power for the operation of the packing and elevating mechanisms presently to be described. The side rails of the main frame are held and braced in suitably spaced relation by the provision of a rear cross frame 21, of inverted U shape, which is connected at its center point to the rear depending leg 22 of

25 a fore and aft top frame 23, the forward leg 24 of which extends downwardly and makes a connection with the forward cross rail 13 of the main frame. This arrangement affords a main frame, which is open at its rear end to clear the deposited shock, and is supported centrally in such manner as to afford ample unobstructed working space for the rotating movements of the pan.

40 45 The inner pan-supporting frame.

The front bar of the main frame constitutes a point of pivotal attachment for an inner frame, comprising outer and inner side arms 25 and 26, which are integrally connected at their forward ends with a cross connecting rod 27, (see Fig. 6) which gives to the inner frame the form of a horizontally disposed U-shaped figure open at its rear end; and the inner frame is pivoted to rock on a horizontal transverse axis, by the provision of journal plates 28 which pivotally connect the forward corners of the inner frame with the corresponding corners of the main or supporting frame. The inner frame furnishes a mounting for the suspension of the open sided pan 29 which diverges from rear to front and is provided in its center with a longitudinally extending channel or depression 30 of a size to receive and initially position the first sheaf delivered,

which thus constitutes a foundation upon which the remaining sheaves are built up in symmetrical relation. The body of the pan is formed of sheet metal, and the upper edges of the pan are reinforced by the provision of side bars 31, which furnish the main elements of a supporting frame or cradle 32 which affords sufficient rigidity to the pan as a whole.

70 The pan is associated with a pair of tread members 33 of arcuate formation, the normally lower portion 34 of each tread member being flattened to clear the ground when the pan is in its normal or receiving position. The flattened portions are formed to extend 75 in substantial parallelism with the bottom edges of the pan, and the treads and pan form in effect a rigidly united structure which moves as a unit when the tread members are brought into ground engagement. 80 The pan is united to the tread members by the provision of rear connecting bars 35 and front connecting bars 36, one of the latter being shown in Fig. 3.

85 The tread members are suitably braced by radial brace members 37 suitably disposed to afford the necessary rigidity to permit the load in the pan to be deposited without unduly straining or rocking the structure as a whole. These braces are connected with parts presently to be described, which in turn are pivotally mounted with respect to the side arms of the inner frame on each side, so that the pan, the treads, and all portions of the structure which rotate in unison with the movements of the pan will rotate about an axis having a definite bearing point with respect to the inner frame.

90 95 The packer and trip mechanism.

100 The packer and trip mechanism is located on the outside of the pan, and is illustrated in detail in Fig. 4. At a point coincident with the axis of rotation of the pan is located a stub shaft 39 which is journaled through 110 a bracket bearing 40 carried by the outer rail 25 of the inner or oscillating frame. The shaft at its outer end has splined thereto a main sprocket wheel 41 which imparts rotation to a bevel faced inner gear 42 located 115 between the pan and the adjacent rail 25. A center bracket casting 43 is freely mounted upon the shaft 39 behind the inner bevel faced gear 42, and this casting 43 furnishes a center connection for the brace bars 37 and 38, and furnishes a hub for the outer tread member.

120 125 The main sprocket wheel 41 engages a sprocket chain 44 which is carried around an idler 45 mounted upon a swinging arm 46 pivotally supported at its upper end from a plate 47, which is normally held in advanced position by the action of a spring 48 (see Fig. 5). The plate 47 is pivotally mounted within a recess in the bracket bear-

ing 40 and is provided with a stop 49 for limiting the freedom of movement between the plate 47 and the arm 46, which two elements are intended to move substantially in unison save for the slight freedom of action indicated. The plate 47 is provided with a rearwardly extending finger 50 which lies immediately beneath a spring-backed detent finger 51 on a trip dog 52, which engages a notch 53 in the forward edge of a segment bar 54, which bar has a radius of curvature concentric with the axis of movement of the oscillating inner frame; and the bracket bearing 40 is provided with a slotted 10 guide extension 55 which embraces the segment and is designed to ride thereupon without permitting any appreciable lateral or distortional movement of the parts, this arrangement serving to steady and support 15 the inner frame during its up and down movements, and to afford the necessary support to permit the overturning movements of the pan. The latch dog and segment may be duplicated on the opposite side of the machine and operated through the medium of companion draw rods 56, which connect with companion rocking fingers 57 at the opposite ends of a rock shaft 58 journaled in parallel 20 relation to the forward cross connection for the oscillating inner frame.

The center bracket casting 43 which is mounted to rotate about the stub shaft 39 carries on the side normally to the rear a journal bracket 59 which journals a crank 35 shaft 60 having at its normally forward end a bevel pinion 61 which meshes with the bevel faced gear 42, and the opposite end of the shaft carries a crank 62 having pivoted thereto a link 63 which connects 40 with a packer crank 64 outwardly projecting from a packer rock shaft 65 journaled in parallel relation to the outer edge of the pan. The packer crank, being longer than the driving crank 62, will have the rotary 45 movements of the latter transformed into an oscillating movement, thereby rocking the packer shaft 65, by the employment of power derived from the advance of the machine. The packer shaft is provided with a pair of 50 tines or fingers 66 which, when the shaft is rocked, will swing down over the open upper side thereof and press upon the sheaves deposited therein, after the pile of sheaves has risen to a given point, and thereafter the 55 oscillation of the tines will subject the parts to an increase in pressure as the pile is further accumulated.

The sprocket chain 44 passes over a rear sprocket wheel 67 driven by the rear outer 60 ground wheel, so that the chain will be constantly rotated, and this rotation will continue to oscillate the packer tines or fingers until the pile on the pan has risen to such a point that the pressure of the tines against the accumulated pile will prevent the normal

movements of the parts, thereby in effect locking the sprocket wheel and gear train against the transmission of power, and in these circumstances the continued pull along the lower course of the chain 44 will have the 70 effect of drawing back the idler arm 46 against the tension of the spring 48, which will result in a kicking up of the detent finger at the tail end of the trip dog, thereby releasing the dog latch and allowing the 75 pivoted inner frame to fall until the tread members engage the ground. Thereafter the pan will rotate with the tread members and associated parts, which rotation will carry the journal bracket 59 around the axial 80 center of the stub shaft 39 at a rate uniform with the speed of rotation imparted to the stub shaft by the travel of the sprocket chain, so that during this period of the operation no relative rotation will be imparted by the bevel faced gear through the 85 engaged pinion, which holds the packer tines in compressed relation against the upending shock until the same has been butted upon the ground in a vertical position. This pressure will be maintained against the shock at a point slightly below the head of the shock, the tines being positioned with a view of supporting the shock at this point, which allows the butts to expand during the upending 90 operation. After the shock is upended, the continued advance of the machine will cause the pressure tines to travel away from the now stationary shock as the pan is swept around in its continued return movement 95 toward its receiving position. To accommodate these movements, the gear ratio between the driving sprocket 67 and the driven sprocket 41 is commensurate with the circumferential ratio between the ground 100 wheel 19 and the tread member 33, which insures the proper rotation of the interlocked bevel gears without the transmission of motion to the packer members during the 105 rotative cycle of the pan.

The compressor.

On the opposite side of the pan is located mechanism whose purpose is to steady the shock during the upending operation and support the same as the pan sweeps over the top of the butted shock, and with this end in view the compressor mechanism is mounted and actuated in such a manner as to carry its effective point of contact toward the rear as the machine advances forwardly, and to maintain this contact until the pan is well above the deposited shock, thereby counteracting any tendency for the pan to upset the shock as it begins its sweep over the top thereof. In designing this mechanism the factors involved pertain to the forward advance of the machine as a whole, to the rotative movement of the pan, and to the varying components of vertical and horizontal 115 120 125 130

travel imparted to the compressor members by the rotation of the pan on which they are mounted. These devices will now be described in detail.

Figures 7 and 9 illustrate the compressor mechanism and associated parts. The compressor arm 68 is mounted upon a compressor rock shaft 69 which is offset at the point 70 to amplify the effect of the rocking movements of the shaft 69. The shaft is journalled within a sleeve 71 and is acted upon by a coil spring 72 which normally has the effect of swinging the offset outer end of the shaft with the compressor arm 68 mounted thereon into upward position, so that the arm will lie back from the open mouth of the pan in such position as to afford no obstruction to the depositing of the sheaves therein.

The sleeve 71, as indicated in Fig. 9, is provided with a laterally extending trunnion 73, which is entered through a journal 74 carried by a bracket 75 bolted or otherwise secured to the edge of the pan, or to portions of the structure fixedly associated with the pan, and the trunnion carries fixedly secured to its outer end a small gear segment 76 which meshes with a large gear segment 77, the ratio shown being two to one, for the purpose of speeding the swinging movement of the pressure arm toward the back of the pan at the proper point in the tilting of the pan.

The large segment 77 is carried by a bell crank arm 78, which is pivoted at the end of a pintle 79 outstanding from the side of the pan, and the outer end of the bell crank arm carries a roller 80 which rides upon a fixed cam 81 which is carried by the adjacent rail 40 of the oscillating inner frame, which arm also carries at its end a journal head 82 which receives and journals the outwardly projecting trunnion 83 of a cradle bar, which passes under the pan, said trunnion being aligned with the stub shaft 39 on the opposite side of the pan, so that the alignment of these members fixes the axis around which the pan revolves.

The cam 81, as actually constructed, is shrouded, as shown in Fig. 6, but in Fig. 9 the parts are indicated diagrammatically to better illustrate the co-operative relation, and in this figure the cam is illustrated with the shroud removed. The rear end of the cam is configured to substantially the arc of a circle, with the trunnion 83 as a center, but the forward portion of the cam protrudes quite abruptly, so that as the pan revolves about the trunnion 83 as a center, the roller 80 will initially ride freely over the cam without having any relative movement imparted thereto, but, as the cycle of revolution is continued, the roller will encounter the protuberant forward end of the cam, thereby rocking the bell crank arm

78 and causing a rotative movement of the large segment in an inward direction, which will impart a correspondingly amplified movement to the small segment, and through it to the compressor rock shaft, which will be swept downwardly, as regards the base of the pan, concurrently with the forward and upward motion of the rear portion of the pan as it tilts forward in the operation of upending the shock. 75

Prior to the motions above described, it is essential that the compressor arm 68 be rocked downwardly into transverse relation to the accumulated shock within the pan, in order to establish an effective contact therewith prior to the beginning of the upending movements. To effect this result, the compressor rock shaft, at its point of forward emergence from the sleeve 71, is provided with a latch head 84 having a notch 85 adapted to be engaged by a dog 86 which is pivoted to a lug 87 depending from the sleeve 71. The head 84 is provided with a tail piece 88, and the dog is likewise provided with a tail piece 89, both of which tail pieces are adapted to ride upon and be supported by a stop finger 90, which extends in a substantially fore and aft direction and is carried by an upstanding arm 91 pivotally mounted at its lower end in a fitting 92 carried by the frame arm 25, a spring 93 serving to hold the arm 91 in retracted position. It will be observed that the latch head 84 and the dog 86 are mounted for movement on separated centers, and the result of this arrangement is that as the pan begins to rotate about the trunnion 83, the tail piece 89 of the dog, being mounted upon a lower center, will first be released from engagement by the stop finger 90 and will fall down into position to engage the notch 85, which through the continued engagement of the tail piece 88 with the stop will be rotated until a latching of the parts is effected. This movement of the parts causes a rocking of the compressor rock shaft and a swinging down of the compressor arms across the shock in the pan during the initial movement of the pan, and after the parts are latched, as above described, the compressor arms will be held in crosswise relation against rotative tension of the spring 72, and this locked relation will continue until the cycle has been completed, at which point the prior engagement of the dog tail piece 89 with the stop finger 90 will unlatch the parts and allow the compressor arms to spring back to vertical position preparatory to the subsequent depositing of the sheaves in the building up of the next succeeding shock. 115 120 125

The elevator.

The elevator for lifting the sheaves from the binder deck to the point of discharge 130

above the pan is well illustrated in Figs. 3 and 6. It consists of a frame comprising side rails 94 which comprise guideways for the upward flight of conveyor chains 95 having cross bars 96 provided with the usual tines or fingers which project at an angle to the guideways during the upward flight and descent in parallel relation to the chain, after the manner usual in such constructions. The chains run over the usual sprocket wheels, which are driven by intermeshing bevel pinions 97, which derive power from the sprocket chain 98 driven by the inner rear ground wheel, but since these features are common in structures of this kind it is not deemed necessary to further describe the details.

The elevator as a whole is carried by brackets 99 which extend upwardly at an angle from the ends of a supporting bar 100, which ends are entered through a pair of clips 101 adjustably mounted upon the proximate side rail 10 of the main frame, which arrangement permits the elevator to maintain a fixed fore and aft relation to the binder deck, and at the same time permits the shocker as a whole to be adjusted in a fore and aft direction in order to bring the pan into proper relation to the delivery point for the sheaves, which is desirable in order to accommodate the shocker to sheaves of varying length and to insure the proper deposit thereof within the pan.

35 *The sheaf arresting and pan locking mechanism.*

During the delivery of the sheaves to the pan it is necessary to provide means for locking the pan against tilting or oscillation, and also to provide for the recurrent opening of the gate, which permits the down passage of the sheaves to the pan, and these mechanisms will now be described.

The supporting bar 35, which connects the rear end of the pan to the proximate tread member, is adapted, on its up swing, to ride over the shoulder latch 102 formed on the lower end of the stop bar 103 which hangs from the rear arch 21, which latch will spring back sufficiently to permit the bar 35 to engage the shoulder, and as the bar slips over the shoulder it will engage a stop 104, so that it will be held firmly locked between the shoulder and the stop during the accumulation of the sheaves in the pan. The engagement with the shoulder is sufficiently slight, however, to cause the parts to clear one another when the oscillating inner frame is unlatched, the pivotal center of the inner frame being so arranged that the falling of the frame and pan will occasion a slight forward movement of these members, so that the pan and associated parts will clear the stops when the pan begins to rotate.

The oscillating packer shaft 65 is provided, at its rear end, with a bent finger 105, which oscillates up and down as the packer shaft is rocked, which finger coacts with a centrally pivoted rocker 106 carried by the bar 35, thereby lifting the opposite end of the rocker and causing the same to engage with the inner end of a bell crank lever 107 pivoted to the bar 103. The bell crank 107 is connected by means of a draw rod 108 with a spring controlled latch dog 109, the tooth 110 of which engages with a latch head 111 carried by a gate shaft 112, which shaft constitutes a supporting head for a series of tines 113, which constitute a gate for the arresting of the sheaves, the tines coacting with a series of obliquely disposed slide bars 114 extending in obliquely downward relation from the top of the elevator, so that when the gate is held in closed position, as indicated in Fig. 8, the gate tines and slide bars in unison will provide a trough shaped open receptacle for the momentary arresting of the sheaves in their progress to the pan. This arrangement also insures a correct fore and aft position of the sheaves at this point, so that they will descend to the pan in certain and orderly progression.

So long as the pan remains in locked horizontal relation, the finger 105, at the tail end of the packer shaft, will with each return movement effect an unlatching of the gate controlling mechanism, so that the release and falling of the sheaves will occur in alternate timed relation to the active movements of the packer, so long as the bundles are accumulating in the pan. This insures against interference of the sheaves with the packer mechanism on its return movements, and at the same time provides automatic mechanism for suspending the delivery of the sheaves during the period of rotation of the pan in upending the accumulated shock, since the latch releasing mechanism is operated only during the time the pan occupies its normal or horizontal position, the gate remaining locked during the delivery of the shock.

115 *The butting tines.*

In order to insure a correct positioning of the sheaves during the accumulating period, and to provide for a spreading of the base of the shock during the upending thereof, a plurality of butting tines 115 are provided, the upper ends of which are secured to a cross header bar 116 which is supported upon the front leg 24 of the top arch, and the abutting tines are arranged in downwardly diverging relation to one another, the lower ends 117 being given a zigzag or sinuous configuration crosswise of the pan, which zigzag arrangement increases the effective lateral dimension of each tine at its 130

lower end, and facilitates the separation and spreading of the grain stalks, so that as the pan is upended the grain stalks composing the butt end of the shock will be laterally separated and the butt end distended to afford an enlarged base for the shock.

Adjustable tread shoes.

Each of the tread members is provided 10 on its periphery with an adjustable tread shoe 118, which is pivoted at its forward end 119, and secured at its rear end by an adjustable clip 120, so that the radius of action 15 of the arcuate tread members can be increased or diminished within given limits, the tread shoes being located in proper position to occasion an augmented lifting effect at the time the pan is clearing the deposited shock, and the shoe members are made adjustable in order to accommodate the mechanism to shocks of varying height.

The axis of the pan is located at a point below the center of each tread member, and forwardly thereof, so that the lifting effect 25 of the tread members, irrespective of the shoe attachments, will be at a maximum during the time the pan is clearing the deposited shock, and during the cycle of operations the oscillating inner frame and pan 30 will, of course, move up and down in conformity with the movements occasioned by the riding of the tread members over the ground surface.

35 *The operation.*

In operation, with the pan in horizontal or receiving position, the sheaves will be carried by the elevator and discharged onto the sloping guide bars 114 in horizontal relation 40 with their butt ends forward. Each sheaf will be momentarily arrested by the gate as the packer tines are swung down over the open side of the pan. As the tines return to upright position, the gate will open and the sheaf will be dropped into the pan. The first sheaf will assume a position within the depressed center portion of the pan and constitute a base or foundation around and above which the remaining sheaves will be 45 accumulated in symmetrical arrangement. At a given point in the accumulating of the sheaves the packing tines will begin to exert pressure against the sheaves, tending to force them down into a compact mass, and after 50 the sheaves have accumulated to a predetermined amount the pressure of the packing tines will increase to a degree sufficient to overcome the tension of the spring, which normally tends to retract the idler over 55 which the packer drive chain passes. This will arrest the free travel of the chain, and the pull thereof against the idler will effect an unlatching of the oscillating inner frame with the pan and tread members rigidly associated therewith. The tread members will

thus be dropped to position to engage the ground and the revolution of the pan will begin.

As the pan begins to revolve, the compressor members on the opposite side of the 70 pan will begin to act. The first operation of the compressor shaft will be a partial rotation thereof in such direction as to throw down the compressor arms to embrace the shock at a point somewhat to the rear of 75 the center, and the shock will thus be held firmly within the pan by the conjoint action of the packer and compressor members. As the pan is upended, the travel of the roller 80 along the cam 81 will effect a partial rotation of the intermeshing gear segments, which will occasion a back sweep of the compressor shaft toward the base of the 85 pan concurrently with the turning movement of the pan in a forward direction. By the 90 time the pan has assumed a substantially vertical position, the shock will be butted upon the ground, but the arcuate sweep of the rear end of the compressor shaft will continue, in a downward and rearward direction, thereby firmly supporting and forcing 95 down the shock against the ground as the machine advances to clear the shock. The compressive movement of the shaft is speeded or amplified by the adoption of a multiplying gear ratio, which ratio is chosen with due regard to the length of the compressor shaft and the rotative movement of the pan, with the result that the active end 100 of the compressor shaft will move rearwardly as the machine advances and maintain contact with the shock for a sufficient length of time to insure against a toppling over of the shock as the pan sweeps over the top of the shock on its return movement.

105 The arrangement of the butting tines is such that as the shock is being upended the butt ends of the grain stalks composing the sheaves will be laterally separated and the base of the shock distended, the zigzag arrangement of the individual tines and their divergence from the vertical center line serving to afford sufficient resistance to the movement of the butt ends to effect a substantial spreading of the base of the shock.

110 After the shock has been delivered, the continued ground contact of the tread members will carry the pan around to its original position, the acquired momentum serving to swing up the pan to latching position, so 115 that the subsequent oscillation of the pan will be prevented and the pan positively maintained in horizontal position during the accumulating period.

120 The arcuate guide bars 11 in engagement with the opposite rails of the oscillating inner frame serves to insure adequate guiding and support for the free ends of the oscillating frame and to guard the same against torsional strains and to insure a positive 125 130

positioning of the operating parts at all times.

Although the combined packer and trip mechanism above described is primarily designed for use in connection with a grain shucker, it is evident that it might be effectively employed in connection with other classes of mechanism in which it is desired to automatically effect a tripping of the parts by an increase in the pressure, due to an accumulation of material in contact with the packer mechanism, and it is not the intention, unless otherwise indicated in the claims, to confine the use of the combined packer and trip mechanism to grain shockers. The implement as a whole is so designed as to be entirely automatic in its operation, the various mechanisms being so timed and harmonized in action as to perform the cycle of operations necessary in the accumulation and deposit of shocks of grain without any attention on the part of the driver of the harvesting machine; and at the same time the various mechanisms are adjustable to meet the requirements of grain sheaves of varying height and to insure a proper accumulation of the same.

I claim:

1. In a grain shucker, the combination of a tiltable pan, trip mechanism adapted when tripped to permit of the tilting of the pan, packer mechanism adapted to act upon the material accumulated in the pan and means associated with the packer mechanism, and adapted at a predetermined point in such accumulation to actuate the trip mechanism, substantially as described.

2. In a grain shucker, the combination of a tiltable pan, trip mechanism adapted when tripped to permit of the tilting of the pan, packer mechanism adapted to act upon the material accumulated in the pan and means associated with the packer mechanism, and adapted at a predetermined point in such accumulation to actuate the trip mechanism, said packer mechanism being adapted during the tilting operation to maintain contact with the contents of the pan, substantially as described.

3. In a grain shucker, the combination of a tiltable pan, means for supporting the pan in a normally elevated position, means for tilting the pan, trip mechanism for releasing the supporting means and permitting a tilting of the pan, packer mechanism mounted in position to act upon the material being progressively accumulated in the pan, means for intermittently moving the packer mechanism toward the material accumulating in the pan, and connections between the packer mechanism and the trip mechanism and adapted to release the trip mechanism when the packer mechanism encounters a predetermined accumulation of

material within the pan, substantially as described.

4. In a grain shucker, the combination of a tiltably mounted pan, means for supporting the pan in a normally elevated position, means for tilting the pan, trip mechanism for releasing the supporting means and permitting a tilting of the pan, packer mechanism mounted in position to act upon the material progressively accumulating in the pan, means for intermittently moving the packer mechanism toward the material accumulating in the pan, and connections between the packer mechanism and the trip mechanism adapted to release the trip mechanism when the packer mechanism encounters a predetermined accumulation of material within the pan, said packer mechanism being adapted to maintain contact with the contents of the pan during the tilting operation, substantially as described.

5. In a grain shucker, the combination of a tiltably mounted pan, supporting means for holding the pan in elevated receiving position, ground engaging means for tilting the pan to effect a discharge of the contents, an oscillating packer mounted on the pan in position to have its acting end recurrently engage the contents of the pan, trip mechanism for effecting a release of the pan supporting means, driving means for effecting an oscillation of the packer, and means operable by the driving mechanism for effecting a release of the trip mechanism when the pressure on the packer due to an accumulation of material within the pan has developed to a predetermined point, substantially as described.

6. In a grain shucker, the combination of a tiltably mounted pan, supporting means for holding the pan in elevated receiving position, ground engaging means for tilting the pan to effect a discharge of the contents, an oscillating packer mounted on the pan in position to have its acting end recurrently engage the contents of the pan, trip mechanism for effecting a release of the pan supporting means, driving means for effecting an oscillation of the packer, and means operable by the driving mechanism for effecting a release of the trip mechanism when the pressure on the packer, due to an accumulation of material within the pan, has developed to a predetermined degree, the packer driving means being adapted to hold the packer in contact with the contents of the pan during the discharging operation, substantially as described.

7. In a grain shucker, the combination of a revolvably mounted pan, an oscillating packer mounted upon the pan and adapted to recurrently swing into contact with the contents of the pan, ground engaging means for revolving the pan to discharge the con-

tents, and driving means for the packer, adapted during the revolution of the pan to suspend the oscillation of the packer and maintain the same in contact with the contents thereof during the discharging operation, substantially as described.

8. In a grain shocker, the combination of a revolubly mounted pan, an oscillating packer mounted upon the pan and adapted to recurrently swing into contact with the contents of the pan, ground engaging means for revolving the pan to discharge the contents, and driving means adapted during the accumulating period to oscillate the packer, and adapted thereafter to set in action the means for revolving the pan, substantially as described.

9. In a grain shocker, the combination of a revolubly mounted pan, an oscillating packer mounted upon the pan and adapted to recurrently swing into contact with the contents of the pan, ground engaging means for revolving the pan to discharge the contents, and driving means adapted during the accumulating period to oscillate the packer and adapted thereafter to set in action the means for revolving the pan, and to effect a suspension of the packer oscillations during the discharging period and maintain the packer in contact with the contents of the pan, substantially as described.

10. In a grain shocker, the combination of a revolubly mounted pan, ground engaging means for revolving the pan, an oscillating packer mounted upon the pan and provided with an arm for swinging across the pan and in contact with the contents thereof, driving means for normally effecting an oscillation of the packer arm, a trip release member engaged by the driving connections and adapted to be actuated by a restriction of the freedom of movement of the packer arm due to an accumulation of material within the pan, and trip mechanism adapted to be actuated by the movement of the trip release member to effect an actuation of the pan revolving mechanism, substantially as described.

11. In a grain shocker, the combination of a revolubly mounted pan, ground engaging means for revolving the pan, an oscillating packer mounted upon the pan and provided with an arm for swinging across the pan and in contact with the contents thereof, driving means for normally effecting an oscillation of the packer arm, a trip release member engaged by the driving connections and adapted to be actuated by a restriction of the freedom of movement of the packer arm due to an accumulation of material within the pan, and trip mechanism adapted to be actuated by the movement of the release member to effect an actuation of the pan revolving mechanism, the movements of the packer operating mechanism and the pan

revolving mechanism being coordinated to maintain the packer arm in contact with the contents of the pan during the discharging period, substantially as described.

12. In a grain shocker, the combination of a pan, means for normally supporting the pan in elevated receiving position, ground engaging means for revolving the pan adapted to be set in action by a lowering of the pan supporting means, trip mechanism for normally holding the supporting means in elevated position, an oscillating packer arm mounted on the pan and movable therewith, packer driving mechanism including a sprocket chain and a yieldably mounted idler, and connections between the idler and the trip mechanism for disengaging the latter when the normal travel of the sprocket chain is impeded by contact of the packer with the accumulated contents of the pan, substantially as described.

13. In a grain shocker, the combination of a pan, means for normally supporting the pan in elevated receiving position, ground engaging means for revolving the pan adapted to be set in action by a lowering of the pan supporting means, trip mechanism for normally holding the supporting means in elevated position, a packer arm mounted on the pan and movable therewith, packer driving mechanism including a sprocket chain and a yieldably mounted idler, and connections between the idler and the trip mechanism for disengaging the latter when the normal travel of the sprocket chain is impeded by contact of the packer with the accumulated contents of the pan, substantially as described.

14. In combination with a receptacle for material, a mounting for the receptacle adapted to permit a discharging movement thereof when material has accumulated to a predetermined degree, ground engaging means for moving the receptacle to effect a discharge of its contents, packer mechanism adapted to act against the contents of the receptacle, trip mechanism adapted when released to effect an actuation of the pan discharging mechanism, and driving connections for the packer adapted to effect a release of the trip mechanism when the pressure of the mechanism upon the contents of the pan has developed to a predetermined degree, substantially as described.

15. In combination with a receptacle for material, a mounting for the receptacle adapted to permit a discharging movement thereof when material has accumulated to a predetermined degree, ground engaging means for moving the receptacle to effect a discharge of its contents, packer mechanism adapted to act against the contents of the receptacle, trip mechanism adapted when released to effect an actuation of the pan dis-

charging mechanism, and driving connections for the packer adapted to operate freely until the normal movements of the packer are impeded to a predetermined degree by pressure of the packer against the accumulated contents of the receptacle and thereupon to effect a release of the trip mechanism, substantially as described.

16. In combination with a receptacle for material, a mounting for the receptacle adapted to permit a discharging movement thereof when material has accumulated to a predetermined degree, ground engaging means for moving the receptacle to effect a discharge of its contents, packer mechanism adapted to act against the contents of the receptacle, trip mechanism adapted when released to effect an actuation of the pan discharging mechanism, driving connections for the packer, and a yieldable member interposed in said driving connections and adapted to be actuated to effect the release of the trip mechanism when the normal travel of the driving connections is impeded to a predetermined degree by pressure of the mechanism upon the accumulated contents of the receptacle, substantially as described.

17. In a grain shocker, the combination of a revolubly mounted pan, ground engaging means for revolving the pan, compressor mechanism associated with the pan, said mechanism including a rock shaft extending in longitudinal relation to the pan and pivotally mounted on an axis transverse to the pan and having at its acting end a compressor arm, and means actuated by the revolution of the pan for imparting to the rock shaft an amplified movement of its compressing end toward the base of the pan as the pan moves to discharging position, substantially as described.

18. In a grain shocker, the combination of a revolubly mounted pan, ground engaging means for revolving the pan, compressor mechanism carried by the pan, said mechanism including a rock shaft extending in ongitudinal relation to the pan and pivotally mounted on an axis transverse to the pan and having at its acting end a compressor arm, a cam track fixedly mounted in respect to the movement of revolution of the pan, and an amplifying gear train movable with the pan and making contact with the fixed cam for amplifying the degree of movement of the compressor arm on its transverse pivot during the discharging movement of the pan, substantially as described.

19. In a grain shocker, the combination of a revolubly mounted pan, ground engaging means for revolving the pan, compressor mechanism mounted upon and movable with the pan, said compressor mechanism including a rock shaft provided at its end with a transversely extending compressor arm, a journal mounting for the rock shaft,

means for normally holding the rock shaft in position to elevate the compressor arm, latch mechanism actuated by the initial movement of the pan to throw down the compressor arm across the pan and latch the rock shaft in such compressing position during revolution of the pan and adapted to effect an unlatching thereof upon return of the pan to normal position, a transverse pivotal mounting for the rock shaft journal, and means for effecting a pivotal movement of said journal and the compressing end of said rock shaft toward the base of the pan as the latter is revolved to discharging position, substantially as described.

20. In a grain shocker, the combination of a revolubly mounted pan, ground engaging means for revolving the pan, compressor mechanism mounted upon and movable with the pan, said compressor mechanism including a rock shaft provided at its end with a transversely extending compressor arm, a journal mounting for the rock shaft, means for normally holding the rock shaft in position to elevate the compressor arm, latch mechanism actuated by the initial movement of the pan to throw down the compressor arm across the pan and latch the rock shaft in such compressing position during revolution of the pan and adapted to effect an unlatching thereof upon return of the pan to normal position, a transverse pivotal mounting for the rock shaft journal, and means actuated by the movement of the pan for effecting an amplified movement of the acting end of the rock shaft with its compressor mechanism during the discharging movement of the pan, substantially as described.

21. In a grain shocker, the combination of a revolubly mounted pan, ground engaging means for revolving the pan, compressor mechanism mounted on a transverse pivotal axis in advance of the pivotal mounting for the pan and extending rearwardly thereof and including a packer arm, and means actuated by the revolving movement of the pan for turning the packer mechanism on its transverse pivot in a direction to move its acting end toward the base of the pan concurrently with the up-ending of the pan, said means including devices for amplifying the degree of said movement, substantially as described.

22. In a grain shocker, the combination of a revolubly mounted pan, ground engaging means for involving the pan, compressor mechanism mounted on a trasverse pivotal axis in advance of the pivotal mounting for the pan and extending rearwardly thereof and including a packer arm, and means actuated by the revolving movement of the pan for turning the packer arm on its transverse pivot in a direction to move its acting end toward the base of the pan concurrently

with the upending of the pan, said means including gear members of differing ratio for amplifying the movement of the acting end of the packer mechanism toward the base of the pan concurrently with the upending of the pan, substantially as described.

23. In a grain shocker, the combination of a tiltably mounted pan open at its forward end and fixedly positioned vertically extending butting tines adjacent the forward end of the pan, said butting ends diverging at their lower ends to spread the base of the shock during the up-ending of the pan, and means for tilting the pan, substantially as described.

24. In a grain shocker, the combination of a tiltably mounted pan open at its forward end and fixedly positioned vertically extending butting tines adjacent the forward end of the pan, said butting tines having a sinuous formation at points adjacent the open end of the pan, and means for tilting the pan, substantially as described.

25. In a grain shocker, the combination of a tiltably mounted pan open at its forward end and fixedly positioned vertically extending butting tines adjacent the forward end of the pan, said butting tines having a sinuous formation at points adjacent the open end of the pan, and having their lower ends extending in diverging relation to spread the base of the shock during the up-ending operation, and means for tilting the pan, substantially as described.

26. In a grain shocker, the combination of a tiltably mounted pan, packing mechanism adapted to act upon the contents of the pan, delivery mechanism positioned to discharge into the pan, a gate in said delivery mechanism for arresting the discharge therefrom, and connections between the packer mechanism and gate for permitting the opening of the gate in alternation to the active movements of the packer mechanism, and means for tilting the pan, substantially as described.

27. In a grain shocker, the combination of a tiltably mounted pan, packing mechanism adapted to act upon the contents of the pan, delivery mechanism positioned to discharge into the pan, a gate in said delivery mechanism for arresting the discharge therefrom, and connections between the packer mechanism and gate for permitting the opening of the gate in alternation to the active movements of the packer mechanism, the operative relations to said connections being interrupted by the discharging movements of the pan, and means for tilting the pan, substantially as described.

28. In a grain shocker, the combination of a tiltably mounted pan, a packer mechanism associated with and movable with the pan, delivery mechanism positioned to discharge into the pan, a gate in said delivery

mechanism for arresting the discharge therefrom, and connections between the packer mechanism and the gate for opening the gate in alternation to the active packer movements, and means for tilting the pan, substantially as described.

29. In a grain shocker, the combination of a tiltably mounted pan, a packer mechanism mounted upon and movable with the pan, delivery mechanism positioned to discharge into the pan, a gate in said delivery mechanism for arresting the discharge therefrom, and connections between the packer mechanism and the gate for opening the gate in alternation to the active packer movements, said connections being interrupted by the discharging movements of the pan, and means for tilting the pan, substantially as described.

30. In a grain shocker, the combination of a tiltably mounted open sided pan, an oscillating packer mechanism carried by the pan and including a packer adapted recurrently to swing down over the open receiving side of the pan, delivery mechanism in position to discharge into the pan, a gate in said delivery mechanism, and connections between the packer mechanism and said gate for opening the gate in alternation to the active movements of the packer arm, and means for tilting the pan, substantially as described.

31. In a grain shocker, the combination of a tiltably mounted open sided pan, an oscillating packer mechanism carried by the pan and including a packer adapted recurrently to swing down over the open receiving side of the pan, delivery mechanism in position to discharge into the pan, a gate in said delivery mechanism, and connections between the packer mechanism and said gate for opening the gate in alternation to the active movements of the packer arm, said connections being interrupted by the discharging movements of the pan, and means for tilting the pan substantially as described.

32. In a grain shocker, the combination of a main frame comprising a side member and a transverse member, an inner frame pivotally mounted at its forward end for vertical oscillation within the main frame, a pan pivotally mounted within the inner frame, and a segment guide bar upstanding from the main frame and slidably engaged by one of the arms of the inner frame for guiding the latter in its vertical oscillatory movements, substantially as described.

33. In a grain shocker, the combination of a main frame comprising side rails and a cross front connection, an inner frame pivotally mounted at its forward end for vertical oscillation within the main frame, a pan pivotally mounted within the inner frame, a segment guide bar supported by the main

frame and slidably engaged by one of the arms of the inner frame for guiding the latter in its vertical oscillatory movements, a releasable connection between the inner frame and said segment guide bar for normally holding the inner frame in elevated relation, and means for effecting a release of said connection, substantially as described.

34. In a grain shucker, the combination of a main frame comprising side rails and a cross front connection, an inner frame pivotally mounted at its forward end for vertical oscillation within the main frame, a pan pivotally mounted within the inner frame, a segment guide bar upstanding from the main frame and slidably engaged by one of the arms of the inner frame for guiding the latter in its vertical oscillatory movements, a releasable connection between the inner frame and said segment guide bar for normally holding the inner frame in elevated relation, and automatic means for releasing said connection upon an accumulation

of a predetermined amount of grain within the pan, substantially as described.

35. In a grain shucker, the combination of a main frame comprising side rails and a cross front connection, an inner frame pivotally mounted at its forward end for vertical oscillation within the main frame, a pan pivotally mounted within the inner frame, a segment guide bar upstanding from the main frame and slidably engaged by one of the arms of the inner frame for guiding the latter in its vertical oscillatory movements, a releasable connection between the inner frame and said segment guide bar for normally holding the inner frame in elevated relation, and automatic means for releasing said connection upon an accumulation of a predetermined amount of grain within the pan, the actuation of said automatic means being effected by the pressure of the accumulated mass, substantially as described.

HARRY S. DICKINSON.
